UNITED STATES PATENT OFFICE.

FRANK E. SLOCUM, OF DENVER, COLORADO.

TOY.

Application filed January 25, 1922. Serial No. 531,660.

To all whom it may concern:

Be it known that I, FRANK E. SLOCUM, a citizen of the United States, residing at Denver, in the county of Denver and State 5 of Colorado, have invented certain new and useful Improvements in Toys; and I do hereby declare the following to be a full, clear, and exact description of the invention, such as will enable others skilled in the art 10 to which it appertains to make and use the same.

This invention relates to motion toys which comprise a figure, a spring board and means for tripping the spring board, whereby 15 by to impart action to the figure.

The invention consists of a figure simulative of a kicking mule mounted in upright position, whereby the hind legs are adapted to be thrown upwardly and rearwardly 20 simultaneously with a movement of the body, whereby the head is lowered and the rump elevated as in the act of kicking.

Other objects and advantages will be apparent and suggest themselves as the nature 25 of the invention is understood.

While the drawings illustrate an embodiment of the invention it is to be understood that in adapting the same to meet different conditions and requirements, various 30 changes in the form, proportion and minor details of construction may be resorted to without departing from the nature of the invention.

Referring to the accompanying drawings 35 forming a part of the application,

Figure 1 is a side view of a toy embodying the invention,

Figure 2 is a central longitudinal section thereof,

Figure 3 is a rear end view, and

Figure 4 is a detail view of a toy figure folded for convenience and compact storage.

Corresponding and like parts are referred 45 to in the following description and designated in the several views of the drawings by like reference characters.

The toy comprises a figure, a frame, a spring board and tripping means for imparting a vibratory movement to the spring board whereby the figure is actuated to simulate a kicking mule.

The frame comprises side pieces 1, an end piece 2, and a cross piece 3, the latter connecting the side pieces remote from the end piece 2. A block 4 is secured to the side

pieces 1 adjacent the end piece 2 and receives one end of a spring board 5 which overlaps the upper edge of the end piece 2. The spring board 5 closes the top of the 60 frame and is disposed between the upper portions of the side pieces 1.

The tripping mechanism for actuating the spring board 5 comprises a flat shaft 6 journaled at its ends in the upper rear corner 65 portions of the side pieces 1. A crank 7 is attached to the extended end of one of the journals of the shaft 6 and serves as means for rotating the shaft when it is required to vibrate the spring board 5. The shaft 6 70 is rotated in a clockwise direction whereby to depress the rear end of the spring board 5 which when released from the shaft flies upwardly with a quick movement which is 75 essential to the proper action of the figure.

The figure is simulative of a kicking mule and comprises a body 8, fore legs 9 and hind legs 10. The fore legs 9 are fixed and are provided with extensions 11 which enter openings formed in the fixed end of the 80 spring board 5 and block 4. The body 8 adjacent the head is pivoted to the fore legs 9 and the hind legs 10 are pivoted to the body and are free to move with the body and independently thereof. Pins 12 applied 85 to the body 8 are disposed upon opposite sides of the fore legs 9 and constitute stops to limit the movement of the body. Other pins 13 applied to the body 8 are disposed upon opposite sides of the hind legs 10 and 90 serve as stops to limit the movement thereof.

The figure is disposed in upright position with the hind legs 10 resting loosely upon the spring board 5. Upon operating the shaft 6, the rear portion of the spring board 5 is depressed and when clearing the shaft moves vertically by a quick snapping action thereby throwing the rear portion of the figure upwardly and effecting a lowering of the head and an outward rearward movement of the hind legs simulative of the 95 action of a kicking mule.

The construction is such as to admit of the toy figure having the legs folded against the sides of the body, as shown in Figure 4, 105 whereby the figure may be contained within the frame to economize space and for convenience of storing.

What is claimed is:

1. An animated toy comprising a frame, a 110 spring board secured at one end to the frame, tripping means at the opposite end

of the frame for actuating the spring board, a figure simulative of a kicking mule having the legs pivoted to the body and supported in upright position by means of the fore legs which have rigid engagement with the frame and the hind legs resting loosely upon the spring board, and pins applied to the body of the figure and disposed upon opposite sides of the legs whereby to limit the relative movement of the parts.

2. A toy of the character specified comprising a frame embodying side pieces and an end and a cross piece connecting opposite ends of the side pieces, a block secured between the side pieces adjacent the end piece, a spring board closing the top of the frame and attached at one end to said block and extending over the upper edge of the end

piece, a flat shaft journaled between the side pieces and adapted to impart a tripping movement to the spring board, a figure simulative of a kicking mule having the legs pivoted to the body and having extensions at the lower ends of the fore legs entering openings formed in the spring board and block, the hind legs resting loosely upon the spring board, and pins applied to the body and disposed upon opposite sides of the respective legs to limit the relative movements of the parts.

In testimony whereof I affix my signature in presence of two witnesses.

FRANK E. SLOCUM.
